J. H. GOOS

RAIL ANCHOR

Filed Feb. 7, 1925

Inventor

Julius H. Goos

Barnett & Truman
Attorneys

UNITED STATES PATENT OFFICE.

JULIUS H. GOOS, OF ST. PAUL, MINNESOTA.

RAIL ANCHOR.

Application filed February 7, 1925. Serial No. 7,609.

To all whom it may concern:

Be it known that I, JULIUS H. GOOS, a citizen of the United States, residing in St. Paul, in the county of Ramsey and State of

5 Minnesota, have invented certain new and useful Improvements in Rail Anchors, of which the following is a specification.

My invention relates to improvements in rail anchors and has for its primary object the provision of an improved one-piece rail anchor which will firmly grip the base flange of a rail and which is so formed as to provide a depending tie abutment of substantial area adjacent one end of the anchor 15 adapted to bear against one of the side faces of a cross tie.

A more specific object is to provide an improved one-piece rail anchor having two jaws, which may be formed of the same size, or which if desired, may be formed of different sizes so as to fit rails having base flanges of different widths and contours, and which is so formed that when one of said jaw portions is in gripping position 20 on the rail, the other of said jaw portions serves as an abutment which bears against one of the vertical faces of the cross tie or other stationary part of the road bed.

In this connection I contemplate the provision of a tie abutting portion which extends downwardly a substantial distance from the under surface of the rail base, so as to provide a bearing surface suitable for use in connection with hewed or pole ties.

Another object is to provide an improved rail anchor of the above general character, which may be readily and conveniently applied to a rail base at either side of the rail, and which, when in operative position, 40 will maintain a resilient grip on the rail base so as to resist any tendency which the countercreeping, vibration or other disturbing influences may have to displace the anchor or loosen its grip on the rail.

The invention has for further objects, such other new and improved constructions relating to rail anchors, as will be herein-after described and claimed for carrying out the above stated objects, and such other incidental objects as will appear from the description of the preferred embodiment of my invention.

The preferred embodiment of my invention is illustrated in the accompanying drawing, wherein:

Fig. 1 is a fragmentary view in cross section of the base portion of a railroad rail showing one of my improved rail anchor devices applied thereto.

Fig. 2 is a plan view of the construction 60 shown in Fig. 1, and

Fig. 3 is an end view of the rail anchor, illustrating the manner in which it bears against a vertical face of the cross tie.

The rail anchor illustrated herein as a 65 preferred embodiment of my invention, consists of a bar 10 preferably of spring steel, the ends of which are bent in opposite directions to provide hook shaped jaw portions 11 and 11^a. The jaw portions 11 and 70 11^a are so disposed with respect to each other that when one jaw is applied to its operative position on the base 12 of a rail, the other jaw portion extends downwardly 75 from the rail base, so as to abut against a cross tie 13 when the rail is subjected to creeping movement.

The opposite faces 14 and 14^a of the anchor body are preferably provided with 80 relatively low shoulders 15—15^a, so disposed with relation to the jaws 11—11^a as to engage the opposite edge of the rail base 12 when the jaw 11 or 11^a, as the case may be, is applied in its operative position on a rail.

The jaws 11—11^a are preferably bent out of alignment with the body 10, shown best in Figs. 2 and 3, and are each formed so that the distance between the lower surface of the jaw and the adjacent face of the body 10 90 will be less than the thickness of the rail base at the point engaged by said jaw, whereby the jaw or hook portion will be distorted from its normally set position as the jaw is driven upon the inclined surface of the rail base.

The bends of the jaw portions 11—11^a are preferably so formed as to provide a slight clearance beneath the lower edge of the rail base as indicated at 16 in Fig. 1 100 and to provide a relatively large clearance 17 above the rail base, so as to permit the anchor to be applied to the rail with a minimum distortion of the jaw portion.

The distance between the shoulder 15 and the inner face of the jaw 11 is preferably 105 such that when the shoulder 15 snaps into engagement with the opposite edge of the rail base, the inner surface of the jaw will be in engagement with the lower edge of 110

the rail base, thereby limiting the movement of the anchor in the direction of its length, during its application to the rail.

The jaws 11—11^a may, if desired, be 5 formed to fit rails of different thickness, and the shoulders 15—15^a may be so disposed with respect to said jaws as to fit rails having base flanges of different widths, thereby providing a double anchor device, which 10 may be applied to rails of different size and at the same time provide a tie abutment preferably adjacent the shoulder end of the anchor, which extends downwardly from the rail a distance sufficient to make the device 15 suitable for use in connection with hewed or pole ties, such for example, as shown in Fig. 3.

One of the difficulties encountered in rail anchors of the above general type in which 20 no downturned portion is provided to bear against the cross tie, is that the body of the anchor does not obtain a firm bearing against the cross tie, but on the contrary, the corner of the anchor body tends to cut into the 25 curved portion of the pole tie. With the rail anchor construction as herein shown, the downwardly projecting jaw 11^a extends below the curved portion 18 of the tie, so as to bear firmly against the tie at 19.

30 In applying the anchor to a rail, the jaw 11 or 11^a as the case may be, is fitted over one end of the rail base and the anchor driven in the direction of its length transversely of the rail until the shoulder 15 or 35 15^a as the case may be, snaps over the opposite edge of the rail base; at which time the lower edge of the rail base will engage the inner surface of the jaw portion, the anchor being of resilient metal and the jaw 40 being driven upon the inclined surface of the rail base maintains its hold on the rail by spring pressure. In addition to this grip the tendency which the anchor may have to assume a diagonal position across the rail, 45 due to the fact that the tie abutment is at the shoulder end of the anchor, will effect a shackle hold on the opposite edges of the rail base.

I claim:

50 1. A rail anchor comprising a body portion formed with a spring jaw adapted to grip one flange of a rail base and provided at the other end with a shoulder adapted to be moved into engagement with the opposite edge of the rail base by driving said jaw transversely of the rail, said shoulder end of the anchor being provided with a portion which extends downwardly from the body portion and is adapted to bear against 55 the cross tie.

60 2. A rail anchor comprising a body portion formed with a spring jaw adapted to grip one flange of a rail base and provided

with a shoulder to engage the opposite edge of the rail, said shoulder end of the device 65 being bent downwardly with respect to the body portion to bear against a cross tie.

3. A rail anchor comprising a body portion, formed at opposite ends with jaw portions which are so disposed with relation to 70 each other than when one of said jaws is driven into operative engagement with the rail base, the other of said jaws extends downwardly from the rail base to provide a tie abutting portion. 75

4. A rail anchor comprising a bar, the ends of which are bent in opposite directions to provide jaws adapted to grip a base flange of a rail with spring pressure, and provided on opposite sides of the body with shoulders 80 for engaging the opposite edge of the rail base; said jaws being so disposed with respect to each other that one jaw projects downwardly from the rail when the other jaw is in gripping engagement with the rail 85 base flange.

5. A rail anchor comprising a bar, formed at one end with a jaw adapted to grip one flange of a rail base with spring pressure and formed at the other end with a shoulder 90 adapted to snap over the opposite edge of the rail base, and formed at this end with a downturned portion adapted to bear against the tie.

6. A rail anchor comprising a bar formed 95 at one end with a jaw portion adapted to grip one flange of a rail base with spring pressure and formed at the other end with a shoulder adapted to snap over the opposite edge of the rail when the anchor is 100 driven in the direction of its length to force said jaw upon the inclined surface of said rail base flange, the portion of the body adjacent said shoulder being bent downwardly to provide a hooked shape jaw portion 105 adapted to bear against a cross tie.

7. A rail anchor comprising a spring metal bar formed at opposite ends with oppositely disposed jaw portions formed with bends whereby a clearance is provided between the lower surface of the rail base and the anchor adjacent one edge of the rail; said anchor device being formed at opposite ends with shoulders adapted to snap over the opposite edge of the rail base. 110 115

8. A rail anchor comprising a spring metal bar formed at opposite ends with oppositely disposed bends providing jaw portions adapted to grip a base flange of a rail and bear against a tie respectively, said jaw 120 portions being bent out of vertical alignment with said body portion and said body portion being provided at opposite ends with shoulders adapted to have a snap engagement with one edge of the rail base.
